CLAIM

We claim the ornamental design for an automotive wheel, as shown and described.

DESCRIPTION

FIG. 1 is a front perspective view of an automotive wheel of our new design;

FIG. 2 is a front view thereof;

FIG. 3 is a top view thereof;

FIG. 4 is a side view thereof;

FIG. 5 is a bottom view thereof;

FIG. 6 is a side view thereof, opposite FIG. 4; and,

FIG. 7 is a rear view thereof.

The broken lines in the drawings illustrate portions of the automotive wheel that form no part of the claimed design. The stippling indicates a contrast in appearance.
